ATTORNEY

UNITED STATES PATENT OFFICE

WILBUR E. LAGANKE, OF EAST CLEVELAND, OHIO

THERMALLY-RESPONSIVE SWITCH

Application filed September 10, 1928. Serial No. 304,944.

This invention relates to switches of the type which are primarily, although not exclusively, intended for use in connection with panels.

5 An object of the invention is to provide a single blade thermally-controlled switch and, additionally, in such type of switch to provide a construction wherein the switch may be reset by moving the handle portion 10 of the switch once into the off position which will reset the switch so that it may again be moved to the on position to re-establish the circuit which has previously been broken.

15 A further object of the invention is to provide a construction in which the operating handle of the switch carries the movable blade and a thermal element.

An additional feature of construction resides in providing a protecting covering for 20 the thermal element so that it will not be moved to release the movable blade of the switch due to mechanical vibration or other similar causes.

25 Other objects of the invention will appear as the description proceeds.

Reference should be had to the accompanying drawings forming a part of this specification in which

30 Fig. 1 is a side elevation of the switch and the mounting therefor.

Fig. 2 is a side elevation of the switch in its open position.

Fig. 3 is a side elevation of the switch 35 showing the position of the parts when the blade of the switch has been thrown, due to movement of the thermal element.

Fig. 4 is an end elevation of the switch.

Fig. 5 is a bottom plan view of the switch 40 in the position shown in Fig. 3.

Fig. 6 is a detail partial cross section of the thermal element.

The body of the switch is represented at 1 and is provided with a projecting handle 2 which may be grasped in order to operate the switch. The body of the switch is mounted upon a body of insulating material indicated at 3, the pivotal mounting for the switch being upon the pin or similar device 50 which is represented at 4.

Projecting downwardly from the body is an extension 5 which is pivotally connected with a member 6 which has spaced apart legs 7. These legs span a stationary pin 8 which is secured in the mounting 3. Surrounding the member 6 is a spring 9, one end of which seats against the pin 8 and the opposite end of the spring bears against an enlarged head carried by the member 6. The construction which is just described is for the purpose of causing the switch to be thrown quickly to a full open or full closed position as the handle 2 is operated. It is believed that the operation and function of the device which has just been described 65 will be readily understood.

Fixedly mounted upon the body portion 1 is an arm 10 which is of conducting material. This arm at its lower end is provided with a face 11 which is adapted to contact with a conducting member 12. Therefore, the face 11 may be designated as the blade of the switch. In order to prevent arcing between the blade of the switch and the member 12 with which it cooperates there 70 is provided a pivoted member 13, which member is pivoted directly upon the arm 10. This member 13 carries a roller 14, and a spring 15 is attached to the member 13 and also to the body portion 1 of the switch. 75

The function of the spring 15 is to normally urge the roller 14 into contact with the conductor or bus bar 12, particularly when the switch is being moved from open to closed position. The rolling contact between the 80 bus bar 12 and the roller 14 will reduce any arcing to a minimum, and, of course, it is apparent that the electrical connection is established as soon as the roller 14 comes in contact with the bus bar 12. The position of the switch in the initial engagement between the roller and the bus bar 12 is indicated in dotted lines in Fig. 2.

Upon the complete closing movement of the switch member the face 11 establishes contact with the bus bar 12 and this contact is maintained due to the action of the spring 9. When contact between face 11 and bus bar 12 is being broken, the roller 14 remains in contact with the bus bar 12 until the spring 100

9 has compressed over the center, thereupon the roller breaks away from the bus bar with a snap.

The body portion 1 of the switch is made of non-conducting material and, as before explained, the member 10 is pivotally mounted thereon by the pivot screw 16. The pivot member 4 forms a terminal to which the end of a fixed conductor 17 is attached, and connecting the pivot 16 and the pivot 4 is a U-shaped member 18. This U-shaped member may be compared to a hairpin and the looped portion thereof straddles a pin 19 which is mounted upon an insulated portion 22 at the lower end of the member 10. It will, therefore, be apparent that the pin 19 is insulated with respect to the conducting portion 10. Current from bus bar 12 will pass through the pivoted arm 10 to the pivotal point 16, then traverse the U-shaped member 18 to the pivotal point 4, thence to the conductor 17. The foregoing being true when the switch is in its closed position.

The U-shaped member 18 is made of special metal so that when the current passing through the same exceeds a predetermined amount it will cause the member 18 to buckle and the looped end thereof will be caused to bow outwardly, thereby lifting itself away from contact with the pin 19. As soon as this takes place the member 10, which is pivoted to the body portion 1 is free to move about its pivot under the action of the spring 15, thus removing the contact face 11 from engagement with the bus bar 12 and so breaking the circuit. The position of the switch members just described is clearly illustrated in Fig. 3 of the drawings.

The pin 19 is formed with a bevelled forward face, as indicated at 19^a in Fig. 3. In order to reestablish the engagement of the member 18 with the pin 19, it is only necessary to move the handle 2 into the position reversed from that shown in Fig. 3, that is to say to move the handle 2 normally to the off position. This will cause the member 18 to be moved toward the right (referring to Fig. 3), and at the same time the member 10 will move somewhat until the rear end thereof engages with the stop 20. Due to the bevelled surface of the pin 19 the rear leg of the U-shaped member 18 would cam over the pin 19, thus restoring the engagement between the member 18 and the pin 19. Thereupon the switch may be moved so as to bring the contact face 11 into engagement with the bus bar 12 to reestablish the circuit through the switch.

In order to protect the member 18 and to prevent vibratory movement thereof causing the lower end to be released from the pin 19, the cover 21 of insulated material is attached to the body portion 1, preferably at the

points of the members 4 and 16, and the cover member 21 is caused to extend downwardly over the member 18 to a sufficient extent to accomplish its desired purpose, but obviously does not extend to completely cover the member 18 nor to interfere with its intended operation as before described.

From the foregoing description it will be seen that the invention as described provides a thermally-controlled switch with a thermal element directly cooperating with the pole member. The construction is compact and the component parts are few.

Having thus described my invention, I claim:

1. A thermally-controlled electric switch comprising a base member, a stationary contact member mounted thereon, an insulated body portion pivotally mounted upon the base, a movable contact blade member pivotally mounted upon the said body portion, a thermally responsive conducting member mounted upon the said body portion and adjacent the movable contact member, means forming an effective connection between the thermally responsive member and the blade member which connection is released when the thermally responsive member becomes heated to a predetermined amount, and a resilient member cooperating with the movable contact member and moving the said member away from the fixed contact member when the thermally responsive member becomes disengaged.

2. A thermally-controlled electric switch comprising a base member, a stationary contact member mounted thereon, an insulated body portion pivotally mounted upon the base, a movable contact member pivotally mounted upon the said body portion, a thermally responsive member which is electrically in series with the said movable contact member, which thermally responsive member is mounted upon the body portion, inter-engaging means carried by the thermally responsive member and the movable contact member whereby they normally move together, the said inter-engaging means being released when the thermally responsive member becomes heated to a predetermined amount, and means for causing the movable contact member to move about its pivot when released from engagement by the thermal responsive member.

3. A thermally-controlled electric switch comprising a base member, a stationary contact member mounted thereon, an insulated body portion pivotally mounted upon the base, a movable contact member pivotally mounted upon the body, a thermally responsive U-shaped member which extends adjacent the movable contact member, a pin carried by the said movable contact member and adapted to be engaged by the U-shaped thermally responsive member whereby the

two said members normally move together, the said thermally responsive member becoming disengaged from said pin when the thermally responsive member is heated to a predetermined amount; and means for 5 moving the movable contact member with respect to the said thermally responsive member when the aforesaid disengagement takes place.

4. In a thermally-controlled electric 10 switch comprising a base member, a stationary contact member mounted thereon, an insulated body portion pivotally mounted upon the base, a movable contact member pivotally mounted upon the said body portion, means for holding the said movable contact member in a definite relation with respect to the said body portion, said means comprising a thermally responsive conducting member which is in circuit with the 15 movable contact member, the said thermally responsive member and the movable contact member having inter-engaging means which are adapted to be released when the thermally responsive member becomes heated to 20 a predetermined amount, means for moving the said movable contact member when said disengagement takes place, a stop carried by the base with which the movable contact 25 member engages when the switch is moved to off position, the said thermally responsive member and said movable contact member being restored to inter-engaging position when the body portion of the switch is 30 moved to off position.

5. A thermally-controlled switch comprising a base member, a stationary contact member mounted thereon, an insulated body portion pivotally mounted upon the base, a movable contact member pivotally mounted 35 upon the said body portion, a U-shaped thermally responsive conducting member which is mounted upon the said body portion and in circuit with a movable contact member, a pin carried by the said contact member which is normally engaged within the U-shaped member whereby the thermally responsive member and the movable contact member move as a unit, the said thermally 40 responsive member disengaging the said pin when the thermally responsive member is heated to a predetermined degree, means for moving the movable contact member with respect to the thermally responsive member 45 when said disengagement takes place, a stop with which the said movable contact member is adapted to engage when moved to off position, the said pin being provided with a cam surface whereby the U-shaped member cams 50 over the end of the said pin to restore the connection between the movable contact member and the thermally responsive member when the body portion is moved to off position.

6. An electric switch comprising a base

member, a stationary contact member mounted thereon, an insulated body portion pivotally mounted upon the base, a movable contact member carried by the said body portion and having a part adapted to engage with the fixed contact member, a carrier pivotally mounted upon the movable contact member, a roller mounted in the said carrier and adapted to make a contact with the fixed contact member upon the initial closing of the switch, and resilient means cooperating with said carrier to properly position the said roller with respect to the fixed contact member upon the movement of the body portion to close the switch.

7. An electric switch comprising a base member, a stationary contact member mounted thereon, an insulated body portion pivotally mounted upon the base, a movable contact member mounted upon the said body portion and provided with a portion adapted to engage with a fixed contact member, a member mounted upon the movable contact member adapted to make a sliding contact with the fixed contact member in advance of the final contact between the movable contact member and the fixed contact member when the switch is moved to its closed position.

8. A thermally-controlled electric switch comprising a base member, a stationary contact member mounted thereon, an insulated body portion pivotally mounted upon the base, a movable contact member pivotally mounted upon the said body portion, a thermally responsive conducting member mounted upon the body portion and in circuit with the movable contact member, inter-engaging means between the thermally responsive member and the movable contact member whereby the said members normally move as a unit and become disengaged when the thermally responsive member becomes heated to a predetermined amount, a shield carried by the said body portion and overlying the thermally responsive member to prevent release by the thermally responsive member due to vibration, and means for moving the movable contact member with respect to the thermally responsive member when the said members have become disengaged.

In testimony whereof, I hereunto affix my signature.

WILBUR E. LAGANKE.
